UNITED STATES PATENT OFFICE.

ERNEST C. EVERETT, OF NEW YORK, N. Y., ASSIGNOR TO R. E. DIETZ COMPANY, OF NEW YORK, N. Y.

DESIGN FOR A VEHICLE-LAMP.

No. 37,773.

Specification for Design.

Patented Jan. 2, 1906.

Application filed November 20, 1905. Serial No. 288,332. Term of patent 7 years.

To all whom it may concern:

Be it known that I, ERNEST C. EVERETT, a citizen of the United States, residing at New York, in the county of New York and State of New York, have invented a new, original, and ornamental Design for Vehicle-Lamps, of which the following is a specification.

In the accompanying drawing the figure is a side elevation of a vehicle-lamp illustrating the design.

I claim—

The ornamental design for a vehicle-lamp as shown.

ERNEST C. EVERETT.
